(57) **CLAIM**

The ornamental design for side panels for furniture substantially as shown and described.

DESCRIPTION

FIG. 1 is a view of a surface pattern applied to a side panel for furniture; and,

FIG. 2 is a perspective view depicting the pattern of FIG. 1 applied to a lounger.

The broken lines in FIG. 1 depict indeterminate length and width. The portions of FIG. 2 shown in broken line do not form part of the design. The fasteners shown in FIG. 2 do not form part of the design.

1 Claim, 2 Drawing Sheets(56)
